UNITED STATES PATENT OFFICE.

JAMES MASON, OF EYNSHAM HALL, WITNEY, COUNTY OF OXFORD, ENGLAND.

FURNACE FOR BURNING PYRITES.

SPECIFICATION forming part of Letters Patent No. 241,685, dated May 17, 1881.

Application filed December 7, 1880. (No model.) Patented in Great Britain August 4, 1880.

To all whom it may concern:

Be it known that I, JAMES MASON, a subject of the Queen of Great Britain, and residing at Eynsham Hall, Witney, county of Oxford, England, have invented certain Improvements in Furnaces for Burning Pyrites, (for which I have obtained a patent in Great Britain, No. 3,196, dated 4th August, 1880,) of which the following is a specification.

10 My invention, which relates to improvements in furnaces for burning pyrites, has for its object effecting the burning of pyrites ore for the production of sulphurous acid, with the view to its conversion principally into sulphuric acid and the manipulation of the said ore during the process of burning without the aid of manual labor.

The furnace employed for carrying out these operations is constructed with a long, narrow, 20 inclined chamber of fire-brick or other suitable material, and is preferably of rectangular section at the sides and the floor, and is closed at its top with a straight or arched roof. Within the said chamber are arranged a series of fluted cylinders, all of similar size and form, with their axes parallel to each other, and with a suitable space intervening between each two consecutive cylinders. The row or series of cylinders is inclined in accordance with the inclination of the chamber, the amount of inclination depending upon the description of ore to be operated upon. The cylinders are, by preference, made either of cast-iron or of fire-clay, but may be of any other material which suffers 30 little or no deterioration from moderate friction at a red heat while in contact with the gases set free during the process. The shafts of the fluted cylinders, made of wrought-iron or other suitable material, project through both 35 sides of the chamber and are carried in suitable bearings outside of the same, the whole of the bearings being secured to strong iron plates or girders bolted to the sides of the furnace and rigidly held in position. One end of 40 each shaft is furnished with a toothed wheel, and into each of these wheels is geared the thread of a worm. All the worms are fixed upon a revolving shaft carried in bearings along the surface of the bed, the rotation of 45 which shaft produces a corresponding and simultaneous revolution of the cylinders all in the same direction.

At one end of the furnace, above and in front of the first cylinder, is fixed a hopper containing the pyrites ore reduced to the desired size for feeding onto the cylinders. At its lower end the hopper is formed with a slit placed across the furnace and of a length equal to that of the above-mentioned fluted cylinders, while a feed-roller inside the hopper, provided with a regulating-slide and rotated mechanically by means of gearing from the main driving-shaft, 55 delivers the ore onto the cylinders in the desired and regular quantity.

The upper surface of the cylinders is caused to move during rotation from the first toward the second, from the second toward the third, and so on, and the ore delivered upon the first by the hopper is thus carried toward the second and deposited in a heap in front of the latter, 60 which picks it up and carries it forward toward the third, and so on through the whole series until the last cylinder, which drops the ore into the final depository. Thus the upper surface of the cylinders forms an artificial bed and 65 laboratory of the furnace, upon which the usual calcining action is carried out at the same time that the material is gradually and regularly fed into, through, and out of the furnace without the aid of manual labor.

In order that my said invention may be fully understood, I shall now proceed more particularly to describe the same; and for that purpose shall refer to the several figures on the annexed sheet of drawings, the same letters 70 of reference indicating corresponding parts in all the figures.

Figure 1 of the accompanying drawings represents a side elevation of a furnace constructed according to my said invention. Fig. 2 is a 75 longitudinal section of the same. Fig. 3 is a transverse sectional elevation taken along the line 1 2, Fig. 2; and Fig. 4 is a transverse sectional elevation taken along the line 3 4, Fig. 2.

Within the inclined calcining-chamber A is 80 arranged the inclined row of fluted cylinders B, keyed upon the shafts b, which are carried in bearings b' outside the heating-chamber, the said bearings being supported on the longitudinal plates or girders C. Motion is imparted 85 to the said cylinder from the main shaft D by the worms d, gearing with the wheels b², keyed upon the cylinder-shafts b. The main shaft D is supported upon the brackets d', and has mo-

tion imparted to it from the engine or prime mover through the intervention of the worm-wheel d^2 , gearing with the worm d^3 upon the counter-shaft d^4 .

- 5 The hopper E, through which the ore is delivered into the calcining-chamber, is fitted with a slide or valve, e, and feeding-roller e', the former being operated by a screw and hand wheel, 1, as shown clearly in the drawings, while the roller e' is operated from the main shaft D by means of the vertical shaft e^2 , to which motion is imparted by the bevel-wheels e^3 , the top of the said shaft having keyed upon it a worm, e^4 , gearing with a worm-wheel, e^5 , which communicates motion to the feeding-roller by means of the gearing d^6 upon the short shaft d^7 , as shown in Figs. 1 and 3. The calcining-chamber, as shown in the accompanying drawings, is formed with an arched roof made up of sections a, to which lifting-handles a' are attached, in order that the roof may be removed with facility when an inspection of the interior of the calcining-chamber is rendered necessary.
- 25 At one end of the chamber, underneath the hopper, is the fire-grate F, which is provided with an uptake, G, and damper g, and at the same end is also situate the down-flue H, leading into the main flue to the acid-chamber, and fitted with the damper h. At the other end of the furnace is the receptacle I for the burned ore, with an outlet, i, provided with a sliding door, i'. From this receptacle also extends a down-flue, J, having a damper, j, the said flue leading to the chimney. Two air-inlets, K, are arranged one on each side of the receptacle I, and are provided with slides or valves for adjusting the quantity of air to be admitted.

The furnace is operated in the following manner, videlicet: Motion is first imparted to the main shaft D from the engine or prime mover through the gearing hereinbefore described, whereby motion is communicated to the fluted cylinders within the calcining-chamber and to the feed-roller in the hopper. The air-inlets K in the receptacle I, and the damper h in the flue H, are closed, while the damper g in the receptacle G, and the damper j in the down-flue J, are opened. The fire is then lighted in the grate, and allowed to heat the calcining-chamber and the cylinders to a red heat. Ore is then admitted into the hopper, the fire withdrawn, the fire-door and ash-pit-closed, also the damper j in the down-flue J, and the damper g in the uptake G, while the damper h is opened, as well as the air-valves K. As the ore descends through the hopper onto the fore plate or valve it ignites and passes onto the cylinders, whence it is gradually carried forward over the whole length of the bed, as hereinbefore described. The process of burning the ore is thus carried out in a thoroughly regular manner without further manual labor and without any additional fuel. As the burned ore arrives at the far end of the chamber it falls into the receptacle I, and is drawn off through the

sliding door i', which is regulated so as to keep always a certain depth of ore over the opening, to prevent the ingress of air at that point. Any of the fluted rollers may, if necessary, be removed for repairs, either through openings in the sides of the chamber or by lifting them bodily out with their axles after the removal of one of the roof-sections. The quantity of pyrites passed through the furnace in a given time will depend on the speed given to the cylinders, their length, the size or depth of the flutes, and on the inclination of the plane through the axes of the cylinders.

When burning small pyrites with cylinders of, say from twelve inches diameter upward, about six to eight revolutions per hour will probably prove a good working-speed; but for large-sized ore and with cylinders of great diameter and with deep flutes, a less speed may be advisable.

The gearing driving the main shaft, as also that which rotates the feed-roller, may be arranged to admit of different speeds, in order to suit variations in the working.

There is no particular limit to the size of the ore used in the process hereinbefore described, so long as the said ore can be fed mechanically through the hopper; but small ore, and, by preference, all below, say three-fourths-inch cube, will probably produce the best results; but I do not confine myself to this limit. I prefer using the ore in separate sizes—that is, each size in a separate furnace—although this is not absolutely necessary. Thus, dust or very small ore may be one class of grains, from the size of a pea to one-fourth-inch cube; a second class, and from that to a three-fourths-inch cube a third class, and so on to a larger size, and with even more subdivisions.

The length and diameter of the fluted cylinders will necessarily be varied, according to the dimensions of the furnace.

Having now fully described the said invention and the manner of carrying the same into effect, I would observe, in conclusion, that I do not claim herein, *per se*, a furnace having a calcining-chamber with a bed formed of rollers for transporting the material to be operated upon through said chamber; but

What I do claim, and desire to secure by Letters Patent, is—

1. The combination, with a calcining-chamber, a series of fluted rollers in said chamber, and mechanism for rotating said rollers, of a fire-chamber, flues controlled by dampers connecting the fire-chamber with the calcining-chamber, a flue leading to a chimney for carrying off the products of combustion, air-inlets for admitting air directly into the calcining-chamber, and flues independent of aforesaid chimney-flue for carrying off the products of calcination, substantially as described.

2. The combination, with a calcining-chamber, a series of fluted rollers therein, an exterior shaft and gearing for imparting motion from said shaft to said rollers, of a feed-hop-

per extending the width of said chamber, a feed-roller revolving in the throat of said hopper and connected by gearing with the aforesaid shaft, and a regulating-gate, substantially as described, so that the ore is delivered into the calcining-chamber to be carried forward by said rollers in a thin sheet and in regulated quantities, as set forth.

3. The combination, with a calcining-chamber, a series of fluted rollers therein, and mechanism for rotating the said rollers, of a feed-hopper, a fire-chamber with flues and dampers, and outlet-flues for carrying off the fumes and gases from the roasting ore at one end of said calcining-chamber, and a flue leading to

a chimney for carrying off the products of combustion from the fire-chamber, air-inlets for admitting air to the roasting ore, and an outlet for the ore at the other end of the calcining-chamber, substantially as described. ²⁰

In testimony whereof I have signed my name to this specification in the presence of two subscribing witnesses.

JAMES MASON.
